UNITED STATES PATENT OFFICE

JOHN McWILLIAMS STONE, OF ST. CHARLES, ILLINOIS, ASSIGNOR TO OPERADIO MANUFACTURING CO., OF ST. CHARLES, ILLINOIS, A CORPORATION OF ILLINOIS

DESIGN FOR A LOUD-SPEAKER

Application filed July 26, 1929. Serial No. 32,216. Term of patent 14 years.

To all whom it may concern:

Be it known that I, JOHN McWILLIAMS STONE, a citizen of the United States, residing at St. Charles, in the County of Kane and State of Illinois, have invented a new, original, and ornamental Design for Loud-Speakers, of which the following is a specification, reference being had to the accompanying drawing, forming a part thereof, in which—

Fig. 2 is a plan view of the loud speaker.

I claim:

The ornamental design for a loud speaker, as shown.

JOHN McWILLIAMS STONE.
